Primary Examiner — Susan E Krakower*Assistant Examiner* — Jerry Shiuan-Hua Hsu(74) *Attorney, Agent, or Firm* — Daryl R. Wright; Greg Carr(57) **CLAIM**

We claim the ornamental design for a wheelie bar, as shown and described.

DESCRIPTION

FIG. 1 is an upper, right, front perspective view of a wheelie bar showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is a lower, left, rear perspective view thereof.

In the drawings, the broken lines illustrate portions of the wheelie bar that form no part of the claimed design.
